DESIGN FOR A CIGARETTE BOX OR ARTICLE OF SIMILAR NATURE

Charles L. Fordyce, New York, N. Y., assignor to Pitman-Dreitzer & Co., Inc., New York, N. Y., a corporation of New York

Application May 17, 1945, Serial No. 119,596

Term of patent 14 years

(Cl. D85—2)

To all whom it may concern:

Be it known that I, Charles L. Fordyce, a citizen of the United States of America and a resident of New York, in the county of New York and State of New York, have invented a new, original, and ornamental Design for a Cigarette Box or Article of Similar Nature, of which the following is the specification, reference being had to the accompanying drawing forming a part thereof.

design for a cigarette box or article of similar nature.

I claim:

The ornamental design for a cigarette box or article of similar nature, substantially as shown.

CHARLES L. FORDYCE.
